US00D361149S

United States Patent [19]**Wedell**[11] **Patent Number:** **Des. 361,149**[45] **Date of Patent:** ** Aug. 8, 1995

[54] **COMBINED QUARTZ HALOGEN FLOOD
LIGHT ASSEMBLY AND SENSOR HOUSING**

[75] Inventor: **Mark T. Wedell, Germantown, Tenn.**

[73] Assignee: **Thomas & Betts Corporation,
Memphis, Tenn.**

[**] Term: **14 Years**

[21] Appl. No.: **26,258**

[22] Filed: **Jul. 22, 1994**

[52] U.S. Cl. **D26/63**

[58] Field of Search **D26/61, 63, 65;
362/269, 275, 282, 285, 418, 419, 421, 427, 394**

[57] **CLAIM**

The ornamental design for an combined quartz halogen flood light assembly and sensor housing, as shown and described.

DESCRIPTION

FIG. 1 is a top perspective view of the assembly of the subject invention;

FIG. 2 is a front elevation view of the assembly of FIG. 1;

FIG. 3 is a left side elevation view of the assembly of FIG. 2;

FIG. 4 is a top plan view of the assembly of FIG. 2; and, FIG. 5 is a bottom plan view of the assembly of FIG. 2.

FIG. 1

FIG. 2

FIG. 3

FIG. 4

FIG. 5
